FIXED BIRD PROOF GAP

Eugene J. Lehman, Zanesville, Ohio, assignor to McGraw-Edison Company, Milwaukee, Wis., a corporation of Delaware

Filed Jan. 20, 1958, Ser. No. 710,040

4 Claims. (Cl. 313—325)

This invention relates to improvements in fixed gaps associated with electrical equipment of different potentials and more particularly relates to isolator gaps having bird-proofing means associated therewith.

Lightning arresters presently in use include the so-called valve-type arrester which has included therein a plurality of totally enclosed series spark gaps. For various reasons, it is desirable in many applications not to rely upon these internal gaps for the entire isolation of line voltage between the arrester and the equipment to be protected. Thus, it has been the practice heretofore to provide an open air gap (spaced electrodes) between the line terminal of the arrester and the line terminal of, for example, a transformer. Open gaps of the type aforementioned are susceptible to shorting by birds and mammals, etc. which deleteriously affect the coordination of the arrester and the equipment to be protected. Further, open gaps of the type noted are susceptible to much variation in dimension in ordinary field mounting, said variations in and of themselves being undesirable because of the changes in electrical characteristics occasioned thereby.

It is an object of this invention to provide an external isolator gap for two pieces of the electrical equipment having a different electrical potential, said gap maintaining the factory pre-set gap dimension independent of field mounting irregularities or the like.

It is another object of this invention to provide a protected isolator gap for use as aforementioned which has the major advantages of an open gap and eliminates the disadvantages of a totally enclosed gap.

Another object of this invention is to provide an isolator gap as aforementioned wherein a pair of gap electrodes are fixedly mounted in a horizontally aligned position within a protective enclosure whereby said gap electrodes cannot weld together under excessive arcing conditions since the molten metal evolved under those arcing conditions will drop downwardly under the influence of gravity.

It is another object of this invention to provide a protective enclosure or housing for the fixed spaced electrodes forming the gap, said enclosure having open ends which are vertically aligned whereby the cleansing action of the weather will tend to keep the gap area free of contamination.

Another object of this invention is to provide an isolator gap of the type aforementioned wherein the enclosure means may take, for example, the form of a prolated ellipsoid, the ends of which are open and the marginal surfaces are irregularly shaped so as to discourage the perching of birds and small animals to thereby prevent a short circuit between the spaced electrodes.

A further object of the invention is to provide a protected isolator gap as aforementioned wherein the electrical connectors connecting the fixed gap electrodes to the two pieces of electrical apparatus are so arranged so that the mechanical forces upon one of the pieces of electrical apparatus will not be transmitted to the other

2

piece of electrical apparatus along at least one of said conductors, thereby eliminating stresses and breakage that might be caused by a different rate of expansion and contraction of the components of the two pieces of apparatus and/or to prevent the transmission of shocks that might occur during the shipment of the two pieces of apparatus when assembled together for shipment as a unit.

Another object of this invention is to provide protective housing or enclosure means for an isolator gap which is made of high dielectric material, is corrosion resistant, has high manufacturing tolerances, is readily produced by mass production techniques, and is otherwise well adapted for the purposes for which it was designed.

The novel features that are characteristic of the invention are set forth with particularity in the appended claims. The invention itself, both as to its organization and its method of operation, together with additional objects and advantages thereof, will best be understood by the following description of a specific embodiment when read in connection with the accompanying drawings in which:

Fig. 1 is a fragmentary front plan view of two pieces of electrical equipment having the novel isolator gap assembly mounted therebetween;

Fig. 2 is an enlarged top view of the isolator gap assembly shown in Fig. 1;

Fig. 3 is a front plan view partially in section of the isolator gap assembly shown in Figs. 1 and 2;

Fig. 4 is a sectional view along lines 4—4 of Fig. 2; and

Fig. 5 is a sectional view of an alternative embodiment. While the novel isolator gap assembly will be described in connection with its application between line terminal bushing of a transformer and an associated lightning arrester, it will become apparent that the isolator gap assembly may have a larger field of application and, hence, the scope of the claims is not to be limited to the precise description of the environmental surroundings.

Returning now to Fig. 1, a transformer tank 10, normally grounded at G, has an upwardly protruding terminal assembly 11 which is connected to line voltage conductor 16 by a suitable transformer bushing connector cap and guard assembly 12. A more detailed description of the terminal connector and guard assembly 12 is set forth in my copending application having Serial No. 614,905, filed October 9, 1956, and assigned to the same assignee. For purposes of the present application, the terminal connector and guard assembly have been modified slightly to provide an aperture and auxiliary terminal lug 15 for connecting a connector 24 which leads to the isolator gap assembly 30 as shall be explained hereinafter. The lug 15 is in direct electrical connection with the line voltage conductor 16.

A lightning arrester 13, here shown of the general type known as a valve arrester, is mounted upon the transformer tank 10 by suitable mounting means 14. The line terminal end of the lightning arrester has a terminal lug 17 which is adapted to fixedly mount the isolator gap assembly 30 between the lightning arrester 13 and transformer 10 as shall now be described.

The isolator gap assembly 30 comprises a rigid elongated conductor member 18 which may be of, for example, strap copper or the like, which is apertured at one end to fit over and be mounted on the terminal lug 17 of the lightning arrester 13. Fixedly mounted at the other end of the strap-like conductor 18 is a high dielectric protective enclosure or housing means 19 which may be made of material such as electrical grade porcelain or the like which encloses and protects a pair of spaced fixedly

disposed electrodes 21 and 22 which are horizontally aligned within the enclosure means 19. The electrode 21 is attached to and may be integral with the conductor 18 and electrode 22 in the terminal end of conductor 24 which is connected to lug 15 on the transformer bushing terminal connector means 12.

The housing or enclosure means 19 may be of the general shape of a prolated ellipsoid or a sphere, the ends of which are open as shown at 25 and 26, said openings 25 and 26 being vertically aligned one with the other. The upper and lower openings 25 and 26 are preferably irregular in shape so as to afford an insecure perch for birds and small animals which otherwise might tend to perch thereon.

It will be observed that the enclosure means 19 when viewed as in Figs. 1 and 3 shows that the sidewalls defining the openings 25 and 26 at their lowest point such as 27 are still above the horizontally aligned electrodes 21 and 22. The reverse is true of the sidewalls defining aperture 26, namely, that point 28 is substantially below electrodes 21 and 22. Thus, substantial protection for the electrodes is provided against wind driven rain or snow, etc., while at the same time permitting water to go down through the openings 26 and 27 to cleanse the interior of the enclosure 19. The electrodes 21 and 22 are preferably fixedly mounted in the sidewalls of the enclosure means 19 in horizontal alignment, the gap dimension therebetween preferably being factory preset and, hence, not subject to variation as may occur by the normal prior art processes. Further, the horizontal alignment of electrodes 21 and 22 ensures that molten metal from the electrodes occasioned by an exceedingly heavy surge arc will tend to fall downwardly and out and, hence, the molten metal will not weld together the electrodes 21 and 22.

As best shown in sectional view Fig. 4, the electrodes 21 and 22 are fixedly disposed in bore 33 formed centrally of opposed inwardly and outwardly extending bosses 31 and 32, respectively, formed on each side of the housing 19. The bores 33 may be of a substantially larger size than the electrodes 21 and 22 to afford sufficient tolerances necessary for ceramic ware if the housing is to be cast of electrical grade porcelain. The electrodes 21 and 22 are held within their respective bores 33 by suitable means such as lead or cement means.

It may be appropriate to note that the suggested design of the isolator gap assembly 30, wherein the apertures 25 and 26 are of the same contour, insures that the apertures will function equally well even though inverted from the position shown, that is, the aperture 25 below and the aperture 26 above the electrodes 21 and 22.

The conductor 24 between the gap housing and the transformer bushing is preferably made flexible, i.e., of material similar to a battery cable or the like so that any differentials in stress or shocks occasioned by expansion and contraction of the components and/or from shipping the components in assembled relation, will not be transmitted from the transformer bushing 11 to the housing 19 and then to the lightning arrester 13. This prevents breakage of the components. It is to be noted that the conductor 24 is provided with suitable insulation 20 to prevent a short between portions of different electrical potential.

An alternative housing 30' is shown in Fig. 5 which is generally similar to that shown in Figs. 1-4. The major differences are that the sidewalls 35 are straight rather than curvilinear and thus are adapted to a moulding operation of, for example, fiber glass or other suitable dielectric material. It is to be noted in this embodiment that the electrodes 21' and 22' may be directly moulded into bosses 31' and 32'.

Although a specific embodiment of the invention has been shown and described, it is with full awareness that many modifications thereof are possible. The invention, therefore, is not to be restricted except insofar as neces-

sitated by the prior art and by the spirit of the appended claims.

What is claimed as the invention is:

1. An external bird proof opened isolator gap adapted to isolate a valve type lightning arrester assembly from electrical apparatus with which said lightning arrester assembly is associated, said isolator gap comprising first and second electrical conductors, said first conductor being connected at one end to an external open line terminal on said lightning arrester and the other end terminating in a first substantially horizontal electrode, said second conductor having an end connected to a line terminal on said electrical apparatus and the other end terminating in a second substantially horizontal electrode spaced from said first electrode, said second conductor having a flexible portion intermediate the ends thereof, and bird-proof enclosure means surrounding said first and second enclosure means having high side walls to form a hollow housing having a vertical opening with an axis passing between the spaced ends of said first and second electrodes to expose said ends to the atmosphere, the upper surface of said housing forming an edge which has at least one vertical concavity disposed adjacent a vertical plane passing through said gap to provide points which discourage roosting thereon so that adjacent points of said edge lie in different horizontal planes to provide a minimum of horizontal surface upon which animals and birds may be supported.

2. An external bird proof isolator gap adapted to isolate a valve type lightning arrester assembly from electrical apparatus with which said lightning arrester assembly is associated, said isolator gap comprising first and second horizontally extending electrical conductors, said first conductor being connected at one end to an external open line terminal of said lightning arrester and the other end terminating in a first horizontally extending electrode, said second conductor having an end connected to a line terminal of said electrical apparatus and the other end terminating in a second horizontally extending electrode spaced from said first electrode to provide a horizontal air-gap therebetween, one of said first and second conductors having a flexible portion intermediate the ends thereof to prevent transmission of mechanical forces therealong, and bird proofing enclosure means surrounding said horizontally spaced first and second electrodes for rigidly maintaining the horizontal air-gap therebetween, said enclosure means being vertically perforated to provide a vertical opening having an axis passing through said air-gap and exposing said first and second electrodes and the gap therebetween to the cleansing effects of the atmosphere, said housing having an upper end surface formed as a horizontally irregular edge with at least one valley therein to provide points which discourage roosting thereon, the floor of said being adjacent a vertical plane passing through said gap to provide a minimum of horizontal surface for the support of birds and animals in the general region of said gap.

3. A protective outdoor gap for electrical equipment, said gap comprising a first horizontal electrode, a second horizontal electrode horizontally spaced from said first electrode, means for electrically connecting said first electrode to a first electrical device, means for electrically connecting said second electrode to a second electrical device, and a housing of electrical insulating material surrounding said first and second electrodes and the gap therebetween, said housing having a perforation with an axis which passes through said gap vertically to expose said first and second electrodes to the atmosphere, the top end of the walls of said housing forming an edge having a vertical dip adjacent a vertical plane of said gap to provide points which discourage roosting and being sloped with respect to the horizon to provide substantially no horizontal surfaces in the region of said horizontal gap.

4. In combination a first horizontally disposed elec-

trode, a second horizontally disposed electrode horizontally spaced from said first electrode, means for electrically connecting said first electrode to a first electrical device, means for electrically connecting said second electrode to a second electrical device, one of said first and second connecting means being flexible, and a hollow housing of electrically insulating material surrounding said first and second electrodes and the gap therebetween, said housing having a vertical perforation with an axis passing through said gap to expose said electrodes to the cleansing effects of the atmosphere and being formed with at least one depression in its top surface adjacent the vertical plane of said gap to provide points which discourage roosting, said surface being sloped with respect

to the horizontal to eliminate horizontal surfaces therefrom.
